FIG. 1 is a front perspective view of a blood pressure monitor showing our new design;

FIG. 2 is a rear perspective view thereof;

FIG. 3 is an elevation view thereof as viewed from arrow 3 of FIG. 6;

FIG. 4 is an elevation view thereof as viewed from arrow 4 of FIG. 6;

FIG. 5 is a plan view thereof as viewed from arrow 5 of FIG. 6;

FIG. 6 is a left elevation view thereof; and,

FIG. 7 is a right elevation view thereof.
